UNITED STATES PATENT OFFICE.

WILLIAM CLARK, OF CAMPBELTOWN, SCOTLAND.

TURBINE.

No. 819,000.

Specification of Letters Patent.

Patented April 24, 1906.

Application filed July 25, 1905. Serial No. 271,210.

To all whom it may concern:

Be it known that I, WILLIAM CLARK, inland revenue officer, a subject of the King of Great Britain and Ireland, and a resident of 5 Campbeltown, Argyleshire, Scotland, have invented certain new and useful Improvements in Turbines for Steam and other Gases, (for which an application for a patent has been filed in Great Britain, No. 16,544, bearing 10 date July 27, 1904,) of which the following is a specification.

This invention relates to improvements in turbines for steam and other gases; and it essentially comprises a turbine having a 15 spiral chamber which may be subdivided and in which the fluid expands, the nature of the spiral being such that the area of the chamber continually increases to permit of the expansion of the actuating-fluid, and in order 20 that my said invention and the manner of carrying same into practice may be properly understood I have hereunto appended two sheets of explanatory drawings, in which—

Figure 1 is a sectional elevation of a steam-turbine as constructed in accordance with 25 my improvements, and Fig. 2 is a sectional elevation corresponding to and at right angles to Fig. 1, while Figs. 3, 4, and 5 are detail sectional views of modified arrangements 30 of the bearings.

Referring to the drawings, 1 is a shaft or pipe which carries steam to the turbine. The steam is admitted to the shaft 1 by means of the pipe 2 through the slots 3 in the steam-pipe 1; but if the steam-pipe does not rotate these slots are not required. Where the steam-pipe 1 is attached to the turbine and rotates with it, bearings 4 are necessary between pipes 2 and 1, and which bearings may 35 be of any kind suitable for the purpose and rendered steam-tight by stuffing-boxes 5 or in any practicable manner. The steam passes along the pipe 1 and thence into the spiral chamber 6 through the slotted openings 40 7. These openings 7 from the steam-pipe 1 may be of any number, size, and shape. The steam issuing into the chamber 6 impinges upon the concave sides of the spiral 8. The radius vector of the spiral makes one or 45 50 more complete revolutions, as may be found most suitable.

To give a well-balanced effect or pressure and subdivision of the actuating-fluid, this spiral chamber 6 may be subdivided into any 55 number of parts 9 by curved spiral plates 10, and each subdivision may commence at any

point in the chamber. The steam on leaving the chamber 6 impinges on the vanes 11, which are attached to rings 12, these rings being securely attached to the outer covering 13 of the turbine by bolts 14. The steam issuing from the vanes 11 passes around a spiral chamber 15 and may thence be conducted by a pipe to the atmosphere or to a condenser. The chamber 15 is attached 60 to the outer covering 13 of the turbine by bolts 16.

17 represents the side plates of the spiral chamber 6. These side plates are shown as formed in one piece with the pipe 1, so as to 65 revolve with it; but they may be made separately, so that the pipe may remain stationary.

The power may be taken from the pipe 1 or a solid continuation thereof, if it is attached to the turbine or spiral chamber 6, or 70 if the said chamber is not attached to the pipe 1, conveying the steam, the power may be taken from a ring or shaft attached to the side plates 17 or in any other convenient manner.

In the drawings I have shown a condenser attached to the turbine. In this arrangement the steam on issuing from the chamber 15 passes into the rings 18 and is there condensed by the cold water circulating around 75 the turbine, the water entering by the pipe 19 and leaving by the pipe 20. The condensed water falls to the bottom of the rings 18, and passing out by the pipes 21 is conveyed by the pipe 22 to a pump which returns same to the boiler.

If the turbine rotates at a high speed on the steam-pipe 1, I prefer to use bearings of the kind shown in Fig. 3 for the purpose of reducing friction and making the engine-bearings practically steam-tight. In this arrangement steam in the high-pressure portions of the turbine pass into grooved cell 23, which contains balls for the bearings. The pressure in 23 will be lower than the pressure 80 in the turbine where the steam leaves the steam-pipe 1, the pressure in 24 less than in 23, in 25 less than in 24, and in 26 less than in 25, and the escape-steam in 26 will be conveyed by pipe 27 through the side plates to a 85 low-pressure portion of the turbine. As shown in Fig. 4, similar ball-bearings may be fitted between pipes 2 and 1, where the pipe 1 revolves with the turbine at high speed. In 90 this arrangement steam from pipe 2, escaping into cells 28 and 29, is conveyed by a pipe 30 to a low-pressure part of the turbine. As 95 100 105 110

many cells as may be found convenient are put in each bearing.

In the arrangement of bearings shown in Fig. 5 stuffing-boxes are dispensed with, and one or more sets of split rings 31 are substituted therefor, while the rings 32 and 33 hold the rings 31 in position and form the ring-casing.

It will be readily understood that there are various modifications of the arrangements of the working parts which may be made without departing from the principle of my invention. Several such turbines may be put side by side on the same shaft, together with others which rotate in an opposite direction. Steam or gas, not fully expanded, may be taken from one spiral chamber and conveyed to another on the same shaft.

Having now described my invention, what I claim as new, and desire to secure by Letters Patent, is—

1. A turbine having a spiral chamber, plates subdividing the chamber into parts in which the fluid expands, the nature of the spiral being such that the area of the chamber continually increases to permit of the expansion of the actuating fluid.

2. A turbine, having a spiral plate and side plates forming an inner spiral chamber, and plates subdividing said chamber into parts, in combination with an outer covering.

3. A turbine, having a spiral plate and side plates, forming an inner spiral chamber, bear-

ings on which said chamber is rotated, and a pipe mounted in the bearings and provided with openings leading to said chamber, in combination with vanes around said chamber against which the steam impinges.

4. A turbine having a spiral plate and side plates forming a spiral chamber, and curved plates subdividing said chamber into parts in combination with an outer covering.

5. A turbine, having an outer casing, a spiral plate therein forming a spiral chamber, in combination with a chamber having curved subdividing-plates within said chamber.

6. In turbines, the combination comprising an outer covering having a spiral plate therein forming a spiral chamber, a rotating subdivided chamber having curved spiral plates within said spiral chamber, and vanes between said spiral chamber and subdivided chamber.

7. In turbines, the combination comprising an outer covering having a spiral plate therein forming a spiral chamber, a rotating subdivided chamber having curved spiral plates within said spiral chamber, and circulating-pipes.

In testimony whereof I have signed my name to this specification in the presence of two subscribing witnesses.

WILLIAM CLARK.
